SHUTTLE FOR ELECTRICAL WEFT DETECTORS

Filed Dec. 28, 1929

UNITED STATES PATENT OFFICE

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

SHUTTLE FOR ELECTRICAL WEFT DETECTORS

Application filed December 28, 1929. Serial No. 417,245.

This invention relates to improvements in shuttles to be used in connection with electrical weft detectors and it is the general object of the invention to provide a shuttle 5 having a spindle and electric contacts so related and operated as to facilitate the placing of a full cop on the spindle.

Some shuttles are provided with spindles pivoted to one end of the shuttle so as to be moved out of the weft chamber of the shuttle 10 to permit removal of an empty cop and insertion of a full one. These spindles are sometimes provided with screw threads on which the cop is turned so as to hold the latter in position. The turning of the bobbin should take place without disturbing any of the electrical detector parts and it is a further object of my invention to provide means for automatically withdrawing a detector element from the path of the bobbin or cop 20 when the latter is rotated on the spindle.

It is another object of my present invention to provide a cop having a slot therein through which may project part of a spring 25 actuated detector element mounted on the spindle, said element being normally held in non-contacting position when weft is present but moving through the slot when weft is absent. Markers or other aligning devices 30 may be provided, one carried by the shuttle and one by the cop, so that the latter may be placed so as to bring the slot opposite the detector element.

With these and other objects in view which 35 will appear as the description proceeds, my invention resides in the combination and arrangement of parts hereinafter described and set forth in the claims.

In the accompanying drawing, wherein a 40 convenient embodiment of two forms of the invention are shown,

Fig. 1 is a top plan view of the preferred form of shuttle made according to my present invention, the cop and mass of yarn supported by the spindle being shown partly in section,

Fig. 2 is a front elevation of the shuttle, parts being in section,

Figs. 3 and 4 are detailed vertical sections

on lines 3—3 and 4—4, respectively, of Fig. 1, Fig. 4 being on an enlarged scale,

Fig. 5 is a view similar to a portion of Fig. 1 showing the pivoted contact element moved to contacting position because of absence of weft,

Fig. 6 shows the aligning elements with the bobbin and spindle substantially in the position shown in Fig. 1, and

Fig. 7 is a view similar to Fig. 3 but showing a modified form of the invention.

Referring to Figs. 1 and 2, I have shown a shuttle S having an eye E at one end for the delivery of the weft W. The opposite end of the shuttle is provided with a pivot 65 pin 10 which supports the spindle 11 having a bearing portion 12 to cooperate with the pin 10. The spindle is tapered toward the eye end of the shuttle and may be provided with several thin fin-like helical threads 13, 70 the purpose of which is to hold the cop 14 from endwise motion along the spindle when the shuttle is brought to a sudden stop at the end of its flight.

The matter thus far described is of common 75 construction and of itself forms no part of my present invention, the spindle normally being in the horizontal position shown in full lines in Fig. 2 so as to locate the mass of weft within the bobbin chamber C.

In carrying my invention into effect I provide the spindle with a transverse slot 20 and pivot as at 21 a contact element 22. The latter is provided with a yarn engaging projection 23 which is normally urged to assume the 85 position shown in Fig. 5 by a light compression spring 24. The spring is received by a bore 25 in the spindle as shown in Fig. 4 and is held in position by means of a screw 26 threaded into the bore and adjustable to vary 90 the compression of the spring 24.

That end of the detector element 22 which is adjacent pivot pin 10 extends laterally as at 27 from which depends a vertical finger 28. The shuttle is provided with an electric contact plate 29 having an electrode 30 adapted for electrical contact with the finger 28. A second contact plate 31 spaced from the other contact and in this instance above it is connected electrically to the pivot pin 10. 100

Brushes 32 and 33 are adapted for sliding contact with the plates 29 and 31, respectively, as the shuttle is boxed.

The spindle may be provided with a marker of any approved form, in this instance a pin 34 which projects upwardly from the spindle and is located centrally with respect to the latter. An arrow or other form of marker 35 may be placed upon the cop so that when the latter is turned to cause the arrow to point toward the pin 34, the projection 23 will be opposite a longitudinal slot 36 formed in the cop.

In the preferred form of the invention the shuttle has secured to one of the vertical walls 37 thereof which defines the weft chamber a small cam block 38 having an upwardly extending surface 39 which is inclined toward the center of the shuttle. This cam plate is positioned for engagement with the extension 27 and finger 28.

When applying a full cop to the shuttle the spindle will be moved upwardly around the pivot pin to assume the position shown in dotted lines in Fig. 2. As the spindle is raised the arm 27 will engage the cam face 39 and move the detector element 22 around its pivot 21 against the action of spring 24 until the projection 23 lies within the outline of the spindle. The parts are so proportioned that when the spindle is moved to its uppermost position the projection will be located within the slot 20 so that the cop may be slipped over the spindle and rotated thereon without interfering with the detector element. The cop is rotated in order to embed the threads 13 into the interior walls of the cop, the latter being rotated until the mark 35 is in alignment with the mark 34 on the spindle.

The innermost layers of yarn on the cop extend across the slot 36 so that when the spindle is moved downwardly to assume the position shown in full lines in Fig. 2 the projection 23 will be engaged by said coils of yarn to prevent the contact element from moving into engagement with the electrode 30. During weaving, therefore, the brushes 32 and 33 will not be in electrical contact with each other and for this reason the external circuit not shown of which they form a part will be open.

As exhaustion approaches, however, the slot 36 will be uncovered and the projection 23 will be free to move through said slot under action of spring 24 to assume the position shown in Fig. 5. This will cause contact between the finger 28 and electrode 30 so that upon the next arrival of the shuttle in a detecting shuttle box the brushes 32 and 33 will be electrically connected through the plates, the pivot pin, the spindle which is metallic, the contact element 22, and the electrode 30. This will close the external circuit referred to and will bring about a change in the operation of the loom, such for instance

as an exchange of shuttles or stopping of the loom.

When the exhausted cop is to be removed from the shuttle the spindle will be raised as previously described, the effect of which will be to move the extension 23 within the spindle or out of the path of movement of the solid part of the cop so that the latter can be rotated on the spindle to release the same from the threads 13 without interfering with the contact element.

In the modified construction shown in Fig. 7 I provide the spindle with a pivoted contact element 40 having a downwardly and outwardly projecting contact finger 41. The external contact plate 42 on the shuttle is connected directly with a block 43 which is really a consolidation of the cam block 38 and electrode 30 of the preferred form. The block 43 has a surface 44 inclined similarly to the finger 41. The parts in the modification will be so located that when the spindle has the full supply of weft thereon the finger 41 will be spaced in the surface 44 but can move into contact therewith when weft is depleted. When the spindle is moved to the dotted line position shown in Fig. 2 the surface 44 will act to move the contact element and the projection 23 out of the path of the cop as in the preferred form.

From the foregoing it will be seen that I have provided a simple form of contacting element which is so actuated that when the spindle is moved to cop receiving position all portions of the contacting element will be moved out of the path of the cop so that the latter may be rotated to effect embedding of the threads 13 therein. It will further be seen that when the spindle is restored to normal running position the contact element is free to move into contacting position upon depletion of weft. It will also be seen in the modified form of the invention that the contacts within the yarn chamber may be provided with the inclined surface which moves the extension 23 into a safe position when the spindle is moved upwardly to receive a cop.

Having thus described my invention it will be seen that changes and modifications may be made therein by those skilled in the art without departing from the spirit and scope of the invention and I do not wish to be limited to the details herein disclosed, but what I claim is:

1. In a shuttle having a spindle and a weft carrier thereon having a detector slot, a detector element operative to have a normal indicating movement by movement through the slot when the spindle is in normal position and moved out of the slot and rendered inoperative to have indicating movement when the spindle is in raised angular position with respect to the shuttle.
2. In a shuttle having a pivoted spindle

5 on which is normally mounted a cop supplied with weft and having a detector slot, a detector element movably mounted on the spindle and movable within the outline of the cop, and means effective when the spindle is pivoted upwardly to move the element out of the slot and out of the outline of the cop whereby the latter can be rotated on the spindle.

10 3. In a shuttle having a pivoted spindle on which is normally mounted a cop supplied with weft, the cop having a slot therein, a detector element movably mounted on the spindle and having a portion movable into the slot of the cop at weft exhaustion when the spindle is in normal position, and means operated upon upward movement of the spindle to prevent the detector element from entering the slot of the cop.

20 4. In a shuttle having a pivoted spindle to support a slotted weft cop, a detector element movably mounted on the spindle and free to move through the cop when the spindle is in normal position, and means to move the detector element out of the slot in the cop when the spindle is pivoted upwardly to receive a fresh supply of weft.

5. In a shuttle having a pivoted spindle to support a weft cop, a detector element mounted on the spindle and having a portion normally capable of extending beyond the outlines of the spindle and across the outline of the cop when the spindle is in normal position, and means to move the element within the spindle where said element will be incapable of crossing the outline of the cop when the spindle is in raised angular position with respect to the shuttle.

40 6. In a shuttle having a pair of spaced electric contacts and a pivoted spindle to support a weft carrier, said spindle being electrically connected to one of the contacts, an electric detector element mounted on the spindle and normally urged toward the other contact, the element being prevented from movement toward said other contact by engagement of a portion of the detector with yarn, said portion to move into position capable of engagement with the carrier for 45 the weft when engaging said other contact, and means to move the contact element to a position where the portion will be incapable of engagement with the carrier when the spindle is raised to receive a fresh weft carrier.

95. 7. In a shuttle having a pair of spaced electric contacts and a pivoted spindle to support a weft carrier, said spindle being electrically connected to one of the contacts, and 60 electric contact element movably mounted on the spindle and having a portion to lie within the path of movement of some part of the weft carrier when the latter is rotated on the spindle at indication of weft exhaustion, and means to move said contact 65.

element out of the path of movement of the weft carrier when the spindle is pivoted upwardly to receive a fresh supply of weft.

8. In a shuttle having a pair of spaced electric contacts and a pivoted spindle to support a weft carrier, said spindle being electrically connected to one of the contacts, a contact element pivoted on the spindle and tending normally to move into engagement with the other contact but restrained from doing so by presence of weft, and having a part movable through the weft carrier at weft exhaustion to effect engagement with said other contact, and a device operative when the spindle is raised pivotally with respect to the shuttle to prevent movement of the contact element through the weft carrier.

9. In a shuttle having a pair of spaced electric contacts and a pivoted spindle to support a weft carrier, said spindle being electrically connected to one of the contacts, a contact element pivoted on the spindle and tending normally to move into engagement with the other contact but refrained from doing so by presence of weft, and having a part movable through the weft carrier at weft exhaustion to effect engagement with said other contact, and a device operative when the spindle is raised pivotally with respect to the shuttle to prevent movement of the contact element through the weft carrier, said device including a fixed inclined surface on the shuttle to have engagement with the contact element.

In testimony whereof I have hereunto affixed my signature.

RICHARD G. TURNER.
